UNITED STATES PATENT OFFICE

167,392

DRESSER

William Joseph Carr, Gardner, Mass., assignor to
Heywood-Wakefield Company, Gardner, Mass.,
a corporation of Massachusetts

Application March 15, 1951, Serial No. 14,513

Term of patent 7 years

(Cl. D33—6)

To all whom it may concern:

Be it known that I, William Joseph Carr, a citizen of the United States, residing at Gardner, in the county of Worcester and Commonwealth of Massachusetts, have invented a new, original, and ornamental Design for a Dresser, of which the following is a specification, reference being had to the accompanying drawing, forming part thereof, in which:

Fig. 1 is a view in perspective of a dresser showing my new design.

Fig. 2 is a view in front elevation of the dresser shown in Fig. 1.

Fig. 3 is an enlarged showing of a portion of the dresser partially, in section along the line 3—3 of Fig. 2, looking in the direction of the arrows, and partially in perspective.

I claim:

The ornamental design for a dresser, substantially as shown.

WILLIAM JOSEPH CARR.
